UNITED STATES PATENT OFFICE

VALENTINE PIPSHIK, OF NEW YORK, N. Y.

VALVE-GRINDER.

1,206,589.

Specification of Letters Patent. Patented Nov. 28, 1916.

Application filed June 27, 1916. Serial No. 106,215.

To all whom it may concern:

Be it known that I, VALENTINE PIPSHIK, a citizen of the United States, residing at New York, in the county of Bronx and State of New York, have invented new and useful Improvements in Valve-Grinders, of which the following is a specification.

The invention relates to an improvement in valve grinders, particularly designed for use in grinding automobile valves in their seats.

In grinding this type of valve, it has been found that to secure a proper seat it is necessary to reciprocate the valve on its seat following the application of a suitable valve grinding compound, the valve being reciprocated rather than rotated in order to secure contact under any and all conditions, as the valve frictionally rotates in use.

The improved valve grinder comprises a stem formed at one end with a handle and at the opposite end with an appropriately shaped terminal to engage the valve, the stem having a longitudinal movable element and there being provided a coöperating connection between the stem and element to rapidly and rotarily reciprocate the stem and thereby the valve in the movement of the element longitudinally of the stem.

The invention in the preferred form of details will be described in the following specification, reference being had particularly to the accompanying drawings, in which:

Figure 1 is a view in elevation, partly in section, illustrating the improved valve grinder. Fig. 2 is a transverse section on the line 2—2 of Fig. 1.

The improved valve grinder comprises a stem 1 of appropriate length formed at one end as 2, with a screw driver terminal or other appropriate terminal by which the rod may be temporarily connected with the valve disk. The opposite end of the stem is provided with an appropriately formed handle 3, the juncture of the stem and handle being such as to permit independent rotation of the parts, in order that the handle may be utilized to apply sufficient pressure during the grinding operation

without interfering with the rotary movement of the stem.

The stem 1 is longitudinally formed with opposite sinuous grooves 4, these grooves being diametrically opposite and parallel throughout their lengths. Preferably the lateral deviation of the maximum limit of any one phase of the groove is approximately two-thirds the circumference of the stem, so that the stem is reciprocated approximately throughout two-thirds of the circumference. The respective grooves are made up of a series of phases, one merging into another, and the operating element 5 in the form of a sleeve, which is freely slidable on the stem 1, is provided with threaded pins 6, which terminally seat in the respective grooves. It is apparent that reciprocation of the sleeve causes a series of rotarily reciprocating movements of the stem, and thereby of the valve in which the stem is connected, these rotarily reciprocating movements being successively in opposite directions and to a number corresponding to the number of distinct phases of the grooves in the length of the stem. Therefore in a single reciprocal movement of the sleeve longitudinally of the stem, the latter will be oppositely rotarily reciprocated a number of times, thereby rapidly grinding the valve.

Having described my invention what I claim and desire to secure by Letters Patent is:

A valve grinder including a stem, a handle mounted on one end thereof, the opposite end of the stem being integrally formed to engage the valve, said stem being formed with opposite sinuous grooves, and a sleeve slidably embracing the stem and formed at diametrically opposite points with countersunk threaded openings, and pins threaded in said openings and having reduced plain terminals to freely engage the sinuous grooves, the sleeve loosely fitting the stem and the plain terminals of the pins loosely fitting the grooves, whereby to avoid sticking in operation.

In testimony whereof I affix my signature.

VALENTINE PIPSHIK.
